(57) **CLAIM**

The ornamental design for door with photograph frames, as shown and described.

DESCRIPTION

FIG. 1 is an isometric view of the door with photograph frames showing my new design;

FIG. 2 is a front elevational view thereof;

FIG. 3 is a rear elevational view thereof;

FIG. 4 is a right elevational view thereof, the left side being symmetrical; and,

FIG. 5 is a top plan view thereof, the bottom being symmetrical; showing my design.

The broken lines are for illustrative purposes only and form no part of the claimed design.
